US0D1070995S

(12) **United States Design Patent** (10) Patent No.: **US D1,070,995 S**
(45) Date of Patent: ** Apr. 15, 2025

(54) **GAMING MACHINE**

(71) Applicant: **Aristocrat Technologies, Inc. (ATI)**,
Las Vegas, NV (US)

(72) Inventors: **Rajendrasinh Jadeja**, Las Vegas, NV
(US); **Bruce Urban**, Las Vegas, NV
(US)

(73) Assignee: **ARISTOCRAT TECHNOLOGIES,
INC.**, Las Vegas, NV (US)

(**) Term: **15 Years**

(21) Appl. No.: **29/899,836**

(22) Filed: **Aug. 14, 2023**
